UNITED STATES PATENT OFFICE

2,441,623

VENTILATING AND VAPORIZING APPARATUS

Charles F. J. Dupuy, Chicago, Ill., assignor to
O-Cedar Corp'n, Chicago, Ill., a corporation of
Illinois

Application April 23, 1945, Serial No. 589,817

6 Claims. (Cl. 261—125)

1

This invention relates to ventilating and vaporizing apparatus, and more particularly to means for effectively vaporizing a volatile liquid, such as a deodorant, in a vehicle, such as, for example, an airplane, etc.

An object of the invention is to provide simple and effective means for supporting a vaporizing liquid within an air stream flowing into the interior of a vehicle and controlling the extent of volatilization by removable closure means for receptacles for the liquid.

A further object is to provide in conjunction with an air inlet through which a stream of air flows into a compartment, readily attachable means for supporting a container or containers of volatile liquid within the air stream while interfering to a minimum degree with the inflow of fresh air.

A still further object is to provide means for quickly deodorizing the compartment through the use of a volatile liquid supported in effective relation with a stream of incoming air, means being provided for inducing rapid and controlled vaporization.

A further object is to provide in combination with an annular air inlet, means for supporting a container or containers partially within the annular stream, whereby effective suction induces a volatilization of the liquid within the receptacles while interfering to a minimum degree with the inflow of air, and, further, providing means for increasing the suction through use of the receptacle closures when not placed upon said receptacles.

Other objects and advantages will appear as the specification proceeds.

The invention is illustrated, in a preferred embodiment, by the accompanying drawing, in which—

Figure 1 is a perspective view of apparatus illustrating my invention; Fig. 2, a top plan view of the means for suspending the liquid receptacles below the air inlet; and Fig. 3, a sectional detail view, the section being taken as indicated at line 3 of Fig. 2.

In the illustration given, A designates a ceiling or wall air inlet; B, receptacles for a volatile liquid, such as a deodorant; and C, means for suspending the receptacles below the air inlet.

The air inlet fitting A may be of any suitable construction. The embodiment illustrated is a type of fitting commonly employed in the ceilings of airplanes and other vehicles. Since specific claims are not directed to the structure, a detailed description is believed unnecessary. 10 designates a metal member secured to the ceiling or any upper wall of a compartment and providing therein an air space. 11 designates a downwardly and outwardly-extending flange which may be formed integrally with the member 10. Spaced inward-

2

ly from the member 11 is a circular flange 12, which is secured to flange 11 by the spacer bars 13, thus providing an air inlet space 14 between the two flanges. Closing the lower end of the inner flange 12 is a glass panel 15. Usually a light bulb (not shown) is housed above the panel 15.

It will be noted that the above structure provides an annular air inlet through which an air stream may pass downwardly and outwardly into the compartment, thus effectively furnishing ventilation. While the improved apparatus claimed herein functions extremely effectively with this type of inlet, it will be understood that other forms of air inlets may be employed.

15 The receptacles B may be employed singly or plurally and may be of any suitable construction. In the illustration given, each receptacle comprises a glass jar 16 having a threaded top 17 adapted to be engaged by a threaded metal closure 18. Within each jar is a body of vaporizing liquid, such as, for example, deodorant, or liquids for other functions, and the usual supports are provided for maintaining a wick pad at the top of the jar and communicating (not shown) 20 wicks extending downwardly into the liquid.

25 The receptacle supporting means C may be of any suitable construction. In the embodiment illustrated, metal strap arms 19 and 20 are equipped at their upper ends with means for releasably engaging the flange 11. In the illustration given, the upper end of the arm 19 and of the arm 20 is folded back upon itself at 21 and threaded to receive the wing screw 22. Welded to the inner side of strap 20 is a metal strip 23 30 having an inwardly-spaced clamping arm 24 at its upper end.

35 A similar member 23a, provided with a clamping arm 24a, is welded to a strap arm 19, but the member extends downwardly to a greater degree 40 than does member 23 on strap 20.

The strap arm 19 has a lower horizontal section 45. Near each end of the section 25 is secured a bracket arm 26 having upwardly-extending ends 27. A receptacle supporting band 28 is welded to the upwardly-turned ends 27 and also the vertical portions of strap arm 19. Ring 28 has free ends 29 spaced apart and threaded to receive the wing screw 30 by which ready adjustment for 50 clamping a receptacle within the ring is effected.

The strap arm 20 has an inwardly-inclined section 31 on each side and a short horizontal bottom portion 32 which is welded to section 25 of strap 19.

55 Within the lower portion of the inclined section 31 of strap arm 20 is a closure-supporting bracket 33. Each bracket is provided with upwardly-extending arms 34 having inwardly-turned flanges 35. The bracket permits ready sliding of the 60 closure 18 into a secure position where the bot-

tom of the closure 18 rests upon the horizontal section 32 of the arm 20.

The suspending means is so formed as to maintain the receptacles in effective relation with the air stream whereby the vapor will be rapidly drawn off and spread through the compartment. Should the air inlet be modified, a corresponding modification must be made in the suspending means so as to bring the air stream into contact with the vaporizing pads. In the particular structure illustrated, unusually effective vaporization is brought about without interfering to any substantial degree with the incoming air stream. While a portion of the air stream strikes the upper end of the receptacles B, a substantial portion of the top of each member B is located within the annular stream and thus, without direct contact with the stream, is subjected to suction which induces rapid vaporization. With respect to the portion of the pad within the air stream, it will be noted that extremely rapid vaporization will take place due to the fast moving air stream. The suction referred to is enhanced by placing the closures 18 taken from the receptacles B upon the bracket arm supports 33, thus to close off or preclude the uprush of air into the hollow space within the annular air stream. At the same time, the closures are supported adjacent their receptacles and are available for quick application to the receptacles for controlling the extent of deodorization or other vaporizing operation.

In operation, the supporting members C are clamped to the annular flange 11; the receptacles B, filled with deodorant or other volatile liquid, are placed within the clamping bands 29 and secured therein by bringing the ends 30 toward each other. The closures 18 are removed from the receptacles and inserted within the bracket arms 33.

The downward sweep of air from the inlet 14 strikes the outer portion of the vaporizing pads in the receptacles B and creates a suction within the hollow space enclosed by the air stream. The inner portion of the top of each receptacle is therefore subjected to suction, and vaporization proceeds rapidly therefrom. With the arrangement shown, complete deodorization of a compartment, such as that found within an airplane, is accomplished within an extremely brief period. The closure members 18 are then replaced upon the receptacles and vaporization stopped. In the resulting ventilating operation, it will be noted that the apparatus interferes to a minimum degree with the downwardly and outwardly sweeping air currents.

While in the foregoing specification, I have set forth certain specific apparatus for effecting the results indicated, it will be understood that considerable variation can be made and should be made in conjunction with different types of air inlets without departing from the spirit of my invention.

I claim:

1. In combination with an annular ceiling air inlet equipped with a flange, a receptacle containing a volatile liquid, means for suspending said receptacle partially in the air stream of said inlet and partially within the central space within said annular air stream, and means for closing said receptacle to preclude vaporization.
2. In combination with an annular ceiling air inlet adapted to discharge into a compartment an annular stream of air with a central suction area between, a plurality of receptacles containing a volatile liquid, and means for supporting

said receptacles with a portion thereof in said air stream and a portion thereof within said central suction space.

3. In combination with an annular ceiling air inlet adapted to discharge into a compartment an annular stream of air with a central suction area between, a plurality of receptacles containing a volatile liquid, means for supporting said receptacles with a portion thereof in said air stream and a portion thereof within said central suction space, and means for closing said receptacles to preclude vaporization.

4. In combination with a ceiling air inlet of a vehicle, said inlet being equipped with a flange, a receptacle containing volatile liquid and adapted to receive a vaporizing pad extending across the top of said receptacle, means releasably engaging said flange for suspending said receptacle in the air stream of said inlet whereby said stream is impinged upon said pad, and means for opening and closing said receptacle while the same is attached to said ceiling inlet.

5. In combination with a ceiling air inlet of a vehicle, said inlet being annular in shape, a receptacle containing a volatile liquid and adapted to receive a vaporizing pad extending across the top of said receptacle, means for suspending said receptacle in the air stream whereby a portion of said pad receives the impact of said air stream and a portion of said pad lies within the suction area provided by said annular stream, and closure means releasably engaging the top of said receptacle to seal the same from said air stream, said closure member providing a smooth surface upon which said air stream impinges.

6. In combination with an annular ceiling air inlet adapted to discharge into a compartment an annular stream of air with a central suction area between, a plurality of receptacles containing a volatile liquid, means for supporting said receptacles with a portion thereof in said air stream and a portion thereof within said central suction space, means for closing said receptacles to preclude vaporization, and means within said central space for releasably supporting said last-mentioned means when not employed for closing said receptacles transversely to said air stream and below the level of the tops of said receptacles to inhibit the flow of air through said central space and increase the flow of air outwardly over the tops of said receptacles.

CHARLES F. J. DUPUY.
